Filed May 18, 1970, Ser. No. 23,029

Term of patent 14 years

U.S. Cl. D26—1E Int. Cl. D13—99

FIG. 1 is a perspective view of the submersible motor components housing showing my new design;

FIG. 2 is a top plan view of the submersible motor components housing of FIG. 1;

FIG. 3 is a side elevational view of one side of the submersible motor components housing of FIG. 1, the opposite side being a mirror image thereof;

FIG. 4 is another side elevational view, taken at right angles to the plane of FIG. 3, showing another side of the submersible motor components housing, the opposite side being a mirror image thereof; and

FIG. 5 is a bottom view of the submersible motor components housing.

I claim:

The ornamental design for a submersible motor components housing, substantially as shown and described.
